US0D1060309S

(12) **United States Design Patent** (10) Patent No.: **US D1,060,309 S**
(45) Date of Patent: ** Feb. 4, 2025

(54) **SCREEN PROTECTOR PASTING BOX**

(71) Applicant: **Shenzhen KAC Technology Co., Ltd.**,
Shenzhen (CN)

(72) Inventor: **PinYuan Liu**, Shenzhen (CN)

(73) Assignee: **Shenzhen KAC Technology Co., Ltd.**,
Shenzhen (CN)

(**) Term: **15 Years**

(21) Appl. No.: **29/798,612**

(22) Filed: **Jul. 9, 2021**

(51) LOC (15) Cl. **14-03**

(52) U.S. Cl.

USPC **D14/217**

(58) **Field of Classification Search**
